HIS ATTORNEY,

UNITED STATES PATENT OFFICE.

JAMES J. LAWLER, OF MOUNT VERNON, NEW YORK.

DESIGN FOR A PIPE-CO尤PLING.

SPECIFICATION forming part of Design No. 33,179, dated September 4, 1900.

Application filed July 7, 1900. Serial No. 22,881. Term of patent 7 years.

To all whom it may concern:

Be it known that I, JAMES J. LAWLER, a citizen of the United States of America, and a resident of the city of Mount Vernon, county 5 of Westchester, State of New York, have invented and produced a new and original Design for a Pipe-Coupler, of which the following is a specification.

This invention relates to a new, useful, and 5 original design for a pipe-coupler.

The characteristic feature of the design is the long vertical tubular stem, across the base of which a tubular section of dissimilar diameter extends horizontally.

5 The drawings which accompany and form part of this specification illustrate a pipe-coupler of my design, in which—

Figure 1 is a side elevation, and Fig. 2 is an end view of the same.

o Similar letters of reference indicate similar parts.

The design consists of the vertical tubular

portion A, enlarged at its upper end, a horizontal tube B at right angles with and of somewhat-smaller diameter than part A, and 25 the enlarged end C, whose diameter is somewhat larger than that of the part A. The tubular portions B and C extend on opposite sides of the part A, the base and center line forming an inverted letter T, whose lines 30 cross at right angles, and having two ungule of different sizes. This fitting makes a neat finish and presents a pleasing appearance.

Having thus described my invention, what I claim as new and original is—

The design for a pipe-coupler substantially as shown and described.

Signed by me at New York city, New York, this 29th day of June, 1900.

JAMES J. LAWLER.
